(57) **CLAIM**

The ornamental design for a tilt-rotor, as shown and described.

DESCRIPTION

FIG. 1 is a front, perspective view of the tilt-rotor according to a first embodiment of the present design;

FIG. 2 is a front view of the tilt-rotor of FIG. 1;

FIG. 3 is a left side view of the tilt-rotor of FIG. 1, the right side being a mirror image thereof;

FIG. 4 is a rear view of the tilt-rotor FIG. 1; and

FIG. 5 is a top view of the tilt-rotor FIG. 1.

FIG. 6 is a front perspective view of a tilt-rotor according to a second embodiment of the present design, with the rotors in a vertical position;

FIG. 7 shows a front view of the tilt-rotor of FIG. 6;

FIG. 8 shows a left side view of the tilt-rotor FIG. 6, the right side being a mirror image thereof;

FIG. 9 shows a rear view of the tilt-rotor FIG. 6; and

FIG. 10 shows a top view of the tilt-rotor FIG. 6.

FIG. 11 is a front perspective view of the tilt-rotor of FIG. 6 with the rotors in a horizontal position;

FIG. 12 shows a front view of the tilt-rotor of FIG. 11;

FIG. 13 shows a left side view of the tilt-rotor FIG. 11, the right side being a mirror image thereof;

FIG. 14 shows a rear view of the tilt-rotor FIG. 11; and

FIG. 15 shows a top view of the tilt-rotor FIG. 11.

FIG. 16 is a front perspective view of the tilt-rotor according to a third embodiment of the present design;

FIG. 17 shows a front view of the tilt-rotor of FIG. 16;

FIG. 18 shows a left side view of the tilt-rotor FIG. 16, the right side being a mirror image thereof;

FIG. 19 shows a rear view of the tilt-rotor FIG. 16; and,

FIG. 20 shows a top view of the tilt-rotor FIG. 16.

The structural elements depicted by broken lines in FIGS. 3, 8, 13, and 18 have been shown for the purpose of illustrating portions of the tilt-rotor that form no part of the claimed design.

The portions of the bottom of the tilt-rotor, not shown in the drawings, form no part of the claimed design.

1 Claim, 20 Drawing Sheets
